Lloyd F. Overholt, Riverside, Ill., assignors to
International Harvester Company, a corpora-
tion of New Jersey

Application April 3, 1936, Serial No. 72,634
Renewed June 30, 1939

13 Claims. (Cl. 183—26)

This invention relates to an air cleaner. More specifically it relates to an air cleaner of the liquid contact type, commonly known as the oil bath type. In the use of air cleaners for engines, it has been found necessary to use a liquid wetted surface in order to obtain the necessary effectiveness in removing the fine particles. In cleaners of this type, oil is usually mixed with the air stream prior to its contact with a filter medium, such as crimped wire wool or screens. In cleaners of this type difficulty has been encountered with clogging of the filtering material, particularly when chaff or similar organic material is drawn into the cleaner.

15 The object of the present invention is to provide an improved air cleaner of the oil bath type in which the air is first projected against a liquid body and in which a specially designed air path is provided to effectively remove the entrained oil and both the heavy and fine particles present as impurities in the air.

20 Another object is to provide an improved gas and liquid contact unit for intimately contacting the air with the liquid and for effectively removing the liquid from the air stream.

These objects and others relating to constructional details will be apparent from the detailed description to follow. In the drawings:

Figure 1 is a side elevation of an air cleaner embodying the invention with one half broken away by a vertical section substantially through the center line to show the component parts of the cleaner;

Figure 2 is a section on the line 2—2 of Figure 1;
35 Figure 3 is a section on the line 3—3 of Figure 1;
Figure 4 is a section on the line 4—4 of Figure 3; and,

Figure 5 is a section on the line 5—5 of Figure 3. The drawings illustrate a cleaner of the type used for tractor engines. A cylindrical casing 10 open at its bottom end is secured to an annular member 11 which provides means for attaching the cleaner to inlet and outlet conduits. An air inlet conduit 12 centrally positioned within the casing 10 is secured to the member 11. Circumferentially spaced openings 13 in the member 11 provide an outlet from the filtering space between the casing 10 and the inlet conduit 12.

An oil reservoir cup 14 is telescopically fitted over the lower end of the casing 10, abutting at its upper end a flange 15 which is secured to the casing wall. A band 16 circling the casing above the flange 15 provides means formed by the pressed out portions 17 for connecting headed links 18 utilized for securing the cup 14 in posi-

tion. A strap 20 is illustrated extending across the bottom of the cup 14. The remainder of the clamping means, which is not shown, may be of any conventional construction. The cup is removably supported in position whereby it may be readily removed for cleaning and filling with oil. To assist the operator in maintaining the proper oil level, a mark formed by pressed out portions of the cup is provided, as indicated in Figure 1. It will be noted that the lower end of the inlet conduit 12 terminates slightly below the oil level when the cleaner is in a static condition; that is, when air is not flowing through the cleaner in appreciable volume.

A baffle cup 21 is positioned in the oil cup spaced from the end of the inlet conduit 12 in overlapping relation with respect thereto. The lower end of the baffle cup 21 slopes inwardly to a large center opening 22 formed in the bottom, which provides communication between the oil 10 reservoir cup and the interior of the baffle cup. At equally spaced positions the baffle cup 21 is supported in position by brackets 23. Said brackets are secured to the lower end of the casing 10 by bolts 24. Inwardly formed depressions 25 are 15 provided in the lower end of the casing wall 10 to provide pockets for the bolt heads and to offset the plane at which the connection is made, for a purpose hereinafter described.

At the upper end of the baffle cup 21, a plurality of agitating members 26, formed by L-shaped straps of metal, are fastened to the outside of the upper wall and extend radially inwardly, terminating adjacent the inlet conduit 12.

Spaced above the upper edge of the baffle cup 21 a sufficient distance to provide an air flow path, a deflecting baffle 27 contacts the conduit 12 and extends downwardly in spaced overlapping relation with respect to the upper wall portion of the baffle cup 21. Said baffle is secured to the 40 cup 21 by three circumferentially spaced, Z-shaped strap members 28 attached to the baffle and to the cup.

A perforated screen 29, frusto-conical in shape, extends downwardly from the outside wall of the 45 baffle 27 in contact therewith and is clamped in position at its lower end by bolts 24. Said screen may be perforated in any suitable manner to provide a large percentage of its area for the flow of air therethrough and to break up the air flow 50 into a plurality of streams, thus affording a scrubbing action.

In the annular space formed between the casing 10 and the inlet 12, a filtering and oil separating unit is mounted. This unit consists of 55

a plurality of frusto-conical baffles 30. As these baffles are identical in construction, one will be specifically described. Each baffle 30 is provided adjacent the air inlet 10 with a down-turned 5 flange, which contacts and closely fits the conduit. The slope of the baffle downwardly from the inlet conduit to the casing 10 is about 30 degrees, as illustrated. At its lower, outer end, the baffle 30 is curved downwardly with the edge 10 portion being slightly spaced from the casing, as illustrated in Figure 3. This spacing distance is about one-sixteenth of an inch in a practical embodiment of the invention. To provide for spacing and maintaining the baffles 30 in position, vertical bars 31 are fitted in circumferentially spaced indentations 32 formed in the peripheral edges of the baffles. These bars locate the baffles in position with respect to the wall and with respect to their common axis.

20 Each baffle 30 is provided with a plurality of radial slits 33 increasing in width at their lower ends. As shown by the sections of Figures 4 and 5, a small flange 34 is formed at one side of the slits during the forming operation. The remainder of the material pressed out to form the slit is bent upwardly to form a curved flange 35. These flanges serve as deflectors in providing a tortuous air path and as contact elements. The flanges at each side of the slits form between 25 the adjacent slits oil return troughs, by means of which the separated oil and dirt run downwardly in a quiet zone, where the air stream does not hinder its flow, to the lower peripheral edges of the baffles. The oil collected between said 30 edges and the casing runs downwardly through the space provided.

35 Below the lowermost baffle 30, a cylindrical wall 36 is mounted in spaced relation to the casing wall to form an oil return passageway. The upper end 37 of the member is flared inwardly to direct the air away from the returning oil stream. The member 36 extends below the normal liquid level to thereby form an oil return passageway out of the path of the air flow. The lower end wall is clamped in position by the bolts 40 45, the offsets 25 in the casing wall providing the spacing. At the upper end of the member 36, pressed-out portions 38 provide means for spacing the member from the casing. A splash baffle 39 is provided to prevent oil from being thrown up when the vehicle is going over rough ground.

The operation of the cleaner, as above described, will be apparent from the drawings and the above description. Air entering through the conduit 12 impinges the surface of the liquid of the cup 21 depositing a substantial portion of the heavy dirt, a portion of the lighter particles, and some of the chaff and similar organic material. 50 The air, then, passes upwardly carrying with it a substantial amount of oil entrained in contact with the oil in the cup 21. The air with the entrained oil strikes the agitating member 26 and is thereby mixed and agitated to break up 55 the oil particles and to effectively contact the air with the oil particles. The air stream is, then, deflected downwardly by the baffle 27. A large amount of the oil with the entrained foreign material is thrown out against the conical baffle 70 75 28, which acts as a scrubber, breaking up the oil into foam, and thus an intimate contact is made between oil and air. The oil returns to the reservoir 14. The air passes through the perforated screen 29 and upwardly into the filter unit. By means of the frusto conical baffle construction,

as described, with the slits staggered to obtain a tortuous passage, an effective intimate contact is obtained, whereby a high efficiency of dirt and oil removal is accomplished. As the air and the entrained oil pass upwardly, the oil is separated from the air and it flows down the upper walls of the baffles between the flanges 34 and 35. The air passes out through the openings and the oil collects along the casing wall and flows downwardly through the oil return passage formed 10 by the member 36. By this construction, an effective cleaner is provided which is not easily clogged by either organic materials or by a large percentage of dirt and similar particles.

Although applicants have shown and described only a preferred embodiment of their improved air cleaner, it is to be understood that they claim as their invention all gas and liquid contact devices falling within the scope of the appended claims.

What is claimed is:

1. An air cleaner comprising a cylindrical casing open at the bottom, an oil reservoir fitted over the bottom of said casing, an air inlet conduit positioned centrally of the casing and terminating in the reservoir, and a series of spaced frusto-conical apertured baffles in contact with the air inlet conduit and extending downwardly therefrom toward the casing wall, said baffles being formed with staggered slits and with upturned flanges adjacent the slits to form tortuous air paths and oil return troughs between the slits and terminating in slightly spaced relation with respect to the casing wall to form oil return passages.

2. An air cleaner comprising a cylindrical casing open at the bottom, an oil reservoir fitted over the bottom of said casing, an air inlet conduit positioned centrally of the casing and terminating above the normal oil level in the reservoir, a baffle cup extending upwardly in spaced overlapping relation with respect to the air inlet, said cup being in communication with the oil reservoir at its lower end, a deflecting baffle over said cup, a cylindrical member spaced from the casing wall and extending below the normal liquid level and upwardly along the casing wall to form an oil return passageway, an intercepting screen extending downwardly from the deflecting wall to the cylindrical member, and contact material between the inlet conduit and the casing wall.

3. An air cleaner comprising a cylindrical casing open at the bottom, an oil reservoir fitted over the bottom of said casing, an air inlet conduit positioned centrally of the casing and terminating adjacent the normal static oil level in the reservoir, a baffle cup extending upwardly in spaced overlapping relation with respect to the air inlet, said cup being in communication with the oil reservoir at its lower end, an annular deflecting baffle extending radially outwardly from the air inlet conduit above the upper edge of the baffle cup and downwardly in overlapping spaced relation with respect to the upper portion of said cup, a cylindrical member spaced from the casing wall and extending below the normal liquid level and upwardly along the casing wall to form an oil return passageway, an intercepting screen extending downwardly and outwardly from the deflecting baffle to the cylindrical member, and contact and oil separating means between the air inlet conduit and the casing wall.

4. An air cleaner comprising a cylindrical casing open at the bottom, an oil reservoir fitted over the bottom of said casing, an air inlet conduit positioned centrally of the casing and ter-

minating adjacent the normal static oil level in the reservoir, a baffle cup extending upwardly in spaced overlapping relation with respect to the air inlet, said cup being in communication with the oil reservoir at its lower end, an annular deflecting baffle extending radially outwardly from the air inlet conduit above the upper edge of the baffle cup and downwardly in overlapping spaced relation with respect to the upper portion of said cup, and a series of spaced frusto-conical apertured baffles in contact with the air inlet conduit and extending downwardly therefrom toward the casing wall, said baffles terminating in slightly spaced relation with respect to the casing wall to form oil return passages.

5. An air cleaner comprising a cylindrical casing open at the bottom, an oil reservoir fitted over the bottom of said casing, an air inlet conduit positioned centrally of the casing and terminating adjacent the normal static oil level in the reservoir, a baffle cup extending upwardly in spaced overlapping relation with respect to the air inlet, said cup being in communication with the oil reservoir at its lower end, a cylindrical member spaced from the casing wall and extending below the normal liquid level and upwardly along the casing wall to form an oil return passageway, and a series of spaced frusto-conical apertured baffles in contact with the air inlet conduit and extending downwardly therefrom toward the casing wall, said baffles terminating in slightly spaced relation with respect to the casing wall to form oil return passages.

6. An air cleaner comprising a cylindrical casing open at the bottom, an oil reservoir fitted over the bottom of said casing, an air inlet conduit positioned centrally of the casing and terminating adjacent the normal static oil level in the reservoir, a baffle cup extending upwardly in spaced overlapping relation with respect to the air inlet, said cup being in communication with the oil reservoir at its lower end, an annular deflecting baffle extending radially outwardly from the air inlet conduit above the upper edge of the baffle cup and downwardly in overlapping spaced relation with respect to the upper portion of said cup, a cylindrical member spaced from the casing wall and extending below the normal liquid level and upwardly along the casing wall to form an oil return passageway, an intercepting screen extending downwardly and outwardly from the deflecting baffle to the cylindrical member, and contact and oil separating means between the air inlet conduit and the casing wall.

55. 7. An air cleaner comprising a cylindrical casing open at the bottom, an oil reservoir fitted over the bottom of said casing, an air inlet conduit positioned centrally of the casing and terminating adjacent the normal static oil level therein, a baffle cup extending upwardly in spaced overlapping relation with respect to the air inlet, said cup being in communication with the oil reservoir at its lower end, an annular deflecting baffle extending radially outwardly from the air inlet conduit above the upper edge of the baffle cup and downwardly in overlapping spaced relation with respect to the upper portion of said cup, a conical oil retaining baffle below the lower edge of said deflecting baffle extending from the baffle cup toward the casing wall, a conical stream member extending between the deflecting baffle and the casing wall, a cylindrical member spaced from the casing wall and extending below the normal liquid level and upwardly along the casing wall to form an oil return passageway, and a

series of spaced conical baffles in contact with the air inlet conduit and extending downwardly therefrom toward the casing wall, said baffles terminating in slightly spaced relation with respect to the casing wall to form oil return passages, said baffles being formed with staggered radial slits, said slits being formed by upwardly pressed-out portions of the baffles whereby downwardly sloping oil return troughs are formed between adjacent slits.

5. A gas and liquid contact device comprising a vertical cylindrical casing providing an inner wall, a cylindrical member extending centrally of said casing providing an outer wall, said walls together defining a contact space annular in cross section, and a series of spaced frusto-conical baffles positioned in said contact space and inclined in the same direction, the upper edges of the baffles being in contact with the wall to which they lie adjacent and the lower edges being slightly spaced from the wall to which they lie adjacent to form liquid drain passages and said baffles being formed with staggered slits and with up-turned flanges adjacent the slits to form liquid return means between the slits.

9. An air cleaner comprising a casing open in the bottom, an oil reservoir fitted over the bottom of said casing, an air inlet conduit terminating in the reservoir and a series of closely spaced baffles each extending downwardly in the same direction across the casing, the lower edges of the baffles terminating in slightly spaced relation with respect to the casing to thereby form oil return passages, and said baffles being formed with staggered downwardly extending slits and with up-turned flanges adjacent the slits to provide oil return means therebetween.

10. An air cleaner comprising a casing open in the bottom, an oil reservoir fitted over the bottom of said casing, an air inlet conduit terminating in the reservoir, a series of closely spaced apertured baffles each extending downwardly in the same direction across the casing, the lower edges of the baffles terminating in downwardly extending flanges slightly spaced with respect to the casing to thereby form oil return passages, and a wall spaced from the casing and extending from adjacent the lower edge of the bottom baffle to the reservoir to provide an oil drain passage out of the path of the air flow.

11. An air cleaner comprising a cylindrical casing open at the bottom, an oil reservoir fitted over the bottom of said casing, an air inlet conduit positioned centrally of the casing and terminating in the reservoir, and a series of spaced frusto-conical apertured baffles extending from the air inlet conduit toward the casing wall, said baffles being formed with staggered slits and with flanges adjacent the slits at each side thereof to form tortuous air paths and oil return troughs between the slits.

12. A gas and liquid contact device comprising a vertical cylindrical casing providing an inner wall, a cylindrical member extending centrally of said casing providing an outer wall, said walls together defining a contact space annular in cross section, and a series of spaced frusto-conical baffles positioned in said contact space and inclined in the same direction, the upper edges of the baffles being in contact with the wall to which they lie adjacent and the lower edges being provided with liquid drain passages and said baffles being formed with staggered slits and with flanges adjacent the slits at each side thereof to form liquid return means between the slits.

13. An air cleaner comprising a casing open in the bottom, an oil reservoir fitted over the bottom of said casing, an air inlet conduit terminating in the reservoir and a series of closely spaced baffles each extending downwardly in the same direction across the casing, the lower edges of the baffles terminating in slightly spaced relation with respect to the casing to thereby form oil re-

turn passages, and said baffles being formed with staggered downwardly extending slits and with flanges adjacent the slits at each side thereof to provide oil return means therebetween.
